[57] **ABSTRACT**

To remove a tie plate from ballast near a railroad tie and place it on the tie in the proper location to hold a rail, the gripping head of a tie plate setter includes two parallel spaced-apart railroad spikes mounted to the shank portion of a handle by two parallel spaced-apart cross-braces which are welded at right angles to the two railroad spikes and the handle, with the handle having a lower gripping portion bent at a 45° angle to the shank portion adapted to be held in the right or left hand and an upper gripping portion welded to and extending from the lower gripping portion where it joins the shank portion having a grip extending orthogonally thereto and adapted to be held in the other hand. To use the railroad tie plate setting tool, a worker inserts the two spikes of the gripping head into two apertures of the railroad tie plate, while the railroad tie plate is on the ballast near the tie and lifts the plate into the proper position on the tie by rotating the plate setting tool.

FIG. 1

FIG. 4

FIG. 3

FIG. 2

METHOD AND APPARATUS FOR SETTING RAILROAD TIE PLATES

This invention relates to methods and apparatuses for setting railroad tie plates.

A work train several days ahead of time throws off supplies along track which is to be modernized by laying "ribbon rail" (rails which are one-quarter mile long) to replace the old type rail which is 39 feet long. These supplies include spikes, anchors, and new heavy-duty tie plates.

The "Steel Gang" (name given to the crew which lays these new ribbon rails) which includes from 75 to 125 men comes along a few days later removing old rail and replacing it with new ribbon rail one side at a time. This large crew is divided up into smaller crews of workers and machine operators each performing a specific task as it moves down the track. One such crew of three or four men picks up the tie plates dumped by the work train and throws them up parallel to the ties. This crew is followed by a machine which sprays creosote on the ties which have been specially planed and notched for the new plates by an earlier machine.

A second crew of workmen move along the track after the creosote machine and picks up the tie plates by hand. The tie plates are then set in the proper position within a groove on the railroad ties to accommodate rails, with the rails and the tie plates being spiked into the railroad ties.

In the prior art, the tie plates are lifted by hand and placed on the ties. It is believed that tools are not available to lift the tie plates because persons skilled in the art believe that a hook-like arrangement would not be able to pick up the ties, since it is difficult under most circumstances to engage a hook within an aperture of a member resting on a flat surface because the hook is prevented from passing a sufficient distance through the aperture by the flat surface.

Accordingly, it is an object of the invention to provide a novel method and apparatus for setting railroad tie plates.

It is a still further object of the invention to provide a tool that is conveniently used by a single workman and a method of using the tool to lift a tie plate and position it properly on the railroad tie without the workman being splashed with creosote.

In accordance with the above and further objects of the invention, a railroad tie plate setting tool includes a gripping head having two parallel railroad spikes spaced apart by cross-braces and welded to the shank portion of a handle, with the shank portion and a lower gripping portion being formed of a relatively large steel tube bent at approximately a 45° angle to separate the shank portion from the lower gripping portion, the end of the lower gripping portion being adapted to be held in the right hand by a workman and the end of the shank portion being welded to the cross-braces. An upper handle portion is welded to the lower handle and includes a grip to be held in the left or right hand of the user.

In use, the spikes of the plate setting tool are inserted through apertures in the tie plate and into the ballast below the tie plate. The tie plate is then lifted by pivoting the tool and the tie plate is deposited on the tie for fastening by spikes.

The tie plate setting tool of this invention and the method of using it have several advantages over prior art tools and methods for accomplishing the same task,

which are: (1) the tool and method are safer since there is less danger of workmen having creosote splashed in their faces, of slipping on the creosote as they handle the tie plates, or of receiving back injuries; (2) the method is faster than having men handle the tie plates directly. It has been found that the tool is especially efficient because the tie plates are traditionally dropped on ballast material, thus permitting the spikes to be inserted easily through the apertures of the tie plate, with the spikes passing into the ballast material.

The above-noted and other features of the invention will be better understood from the following detailed description when considered with references to the accompanying drawings in which:

FIG. 1 is a fragmentary perspective view of a railroad track showing the tool as it is positioned to locate railroad ties;

FIG. 2 is an elevational front view of the tie plate setting tool of FIG. 1 in accordance with an embodiment of the invention;

FIG. 3 is an elevational side view of the tie plate setting tool of FIG. 1 in accordance with an embodiment of the invention; and

FIG. 4 is a plan view of the tie plate setting tool shown in FIG. 1, taken along lines 4-4 of FIG. 2.

In FIG. 1, there is shown a perspective view of a railroad tie plate setter 10 positioned to move a railroad tie plate 12 into position on a railroad tie 14, which railroad tie cooperates with other railroad ties, one of which is shown at 16, to support rails, one rail being shown in 18. The railroad ties and the unassembled tie plates such as the one shown at 12, rest upon a ballast material indicated generally by the numeral 20 in FIG. 1, which ballast material comprises medium-size rocks that are 2 or 3 inches in diameter.

The railroad tie plate setter 10 is utilized to move the tie plate 12 into position within a depression such as 22 shown in the tie 14.

The tie plates 12 are substantially right, regular, parallelepipeds, having a top surface 24 with an elongated recess 26 adapted to receive a rail and four apertures 28 extending through the tie plate on each side of the slots 26 to accommodate eight spikes for holding the tie plate 24 and the rail to the ties 14 and 16. The apertures have a square cross-section with sides three-quarters inch long, the longest cross-section dimension thus being approximately 1 1/16 inches long.

The tie plate setter 10 includes a tie plate gripping head 30 including projecting spikes which are insertable within two of the apertures 28 of a tie plate and a handle 32 held by an operator during movement of the tie plate 12 into the depressions 22.

To grip the tie plate 12, the tie plate gripping head 30, best shown in FIG. 2, includes two parallel elongated 6 1/4 inch railroad tie spikes 34 and 36 with their heads removed and two parallel cross-braces 38 and 40, each of which is welded at one of its ends to a first of the spikes 34 and at the other of its ends to a second of the spikes 36 to hold the spikes 34 and 36 in rigid, parallel, spaced-apart position. The distance between the two spikes 34 and 36 is equal to the distance between two of the apertures 28 in the tie plate 12, preferably being the same distance as two of the apertures which are adjacent to each other and near the same side of the elongated recess 26. The cross-braces 38 and 40 may also be spikes which have had their pointed tips and heads removed before welding to the spikes 34

and 36 or some other type of sufficiently rigid member.

In the preferred embodiment, the spikes 34 and 36 each have a perpendicular cross-section which is a square with sides five-eighths inches long, and are pointed at their distal ends so as to pass through the tie plate spike holes and into the ballast. The spikes 34 and 36 are preferably spaced 2 $\frac{1}{8}$ inches apart to be insertable into adjacent apertures near the same side of the recess 26 of a tie plate, but may be spaced 2%, 4 5/16, 5%, 6 1/8, 2%, 10 1/2, 4%, 9 1/4, 12, 8 1/2, 4 1/2 or 6 1/4 inches apart to be insertable into other pairs of apertures. The spikes extend downwardly from the cross-brace 38 at least one-half inch and preferably at least 1 1/4 inches.

The handle 32 includes a shank 42, an upper gripping portion 44, a lower gripping portion 50 and a handle brace 46, as best shown in FIG. 3.

To enable the workman to hold the tie plate gripping head 30 conveniently, the shank 42 and lower gripping portion 50 are formed from a one and one-half inch light-gage steel tube approximately 42 inches long, bent to form the shank 42 approximately 8 inches from one end and 27 inches from the other end to form a 10-inch radius bent portion. The shank 42 is welded at its distal end to the two cross-braces 38 and 40 at a location directly between the parallel spikes 34 and 36, with the end of the tube being welded to the lower cross-brace 36 and the side of the tube being welded to the cross-brace 40 so that the spikes 34 and 36 extend at a relatively acute angle to the longitudinal axis of the shank 42.

To enable the tie plate setting tool 10 to be easily pivoted, an upper gripping portion 44 is provided, which upper gripping portion is formed from a $\frac{1}{2}$ inch light-gage steel tube welded at one end to the 1 1/2 inch tube along the 10-inch radius between the shank 42 and the lower gripping portion and extending upwardly therefrom, with the $\frac{1}{2}$ inch tube being bent near its upper end out of the plane passing through the shank, the lower gripping portion, the handle brace and the lower end of the upper gripping portion to accommodate a rubber grip 52, which extends transverse to the longitudinal axis of the unbent portion of the upper handle 44 so that a user of the tie plate setting tool 10 holds the rubber grip 52 in his left or right hand and the end of the lower gripping portion 50 in his other hand when lifting a tie plate 12.

To aid in supporting the upper and lower gripping portions in rigid relationship, the handle brace 46, which is another steel tube, fits between the lower gripping portion 50 and the upper gripping portion 44, being orthogonal to the lower gripping portion 42 and is welded at each end to hold the two gripping portions together.

Of course, the plate setting tool 10 may have dimensions other than those specified above without deviating from the principles of the invention. However, for convenience in use, the grip 52 should be no further than 2 1/2 feet from the lower gripping portion 50 and no closer than 6 inches. Moreover, the pointed ends of the spikes 34 and 36 should be no closer than 2 feet nor any further than 6 feet from the grip 52. The total length of the plate setting tool 10 should be more than 3 feet measured from the pointed ends of the spikes 34 and 36 in a straight line to the end of the lower gripping portion 50.

Before using the tie plate setting tool 10, tie plates 12 are placed at spaced intervals on ballast material 20

(FIG. 1) along the railroad track corresponding to the number of positions on the ties. There is usually creosote on the ties to preserve the ties.

In use, the tie plate setting tool 10 is used to grip the tie plates 12, lift and place them in the depression 22 of the ties 12.

To grip the tie plates 12, the tie plate setter 10 is held with the right or left hand on the lower gripping portion 50 and the other hand holding the hand grip 52. With the tie plate setter 10 held in this manner, the two spikes 34 and 36 are inserted into two apertures in the tie plate 12 as shown in FIG. 1. The tie plate setter tool 10 is then pushed downwardly so that the spikes 34 and 36 move into the ballast material 20, permitting a good grip on the tie plate 12.

To lift the tie plate 12 over the depression 22 and the end of the tie 14, the end grip 52 and the lower gripping portion 50 of the handle 32 are rotated with respect to each other, generally by pushing downwardly on the gripping portion 50 and the entire handle 32 is moved until the tie plate 12 is over the depression 22 in the tie 14. To lower the tie plate into the depression 22 and to remove the spikes 34 and 36, the lower gripping portion 50 and the upper gripping portion are rotated in the opposite directions, thus permitting the tie plate to slide off the spikes 34 and 36 into the depression 22.

With the tie plate 12 in place, new rail is placed in its elongated recess 26 and then spiked down solid.

The tie plate setting tool and the method of using it have several advantages over the prior art tools and methods, which are: (1) they are safer since there is less danger of employees having creosote splashed in their faces, slipping on the creosote as they handle the tie plate or of receiving back injuries; (2) the method is faster than having men handle the tie plates directly. It has been found that the tool is especially efficient because the tie plates are traditionally dropped on the ballast material, thus permitting the spikes 34 and 36 to be inserted easily through these apertures of the tie plate, with the spikes passing into the ballast material.

What is claimed is:

1. A method of setting railroad tie plates onto ties of a railroad track comprising the steps of:
45 placing railroad tie plates on ballast material near railroad ties;
50 inserting at least one elongated pointed member through at least one aperture in the tie plate and into said ballast material;
55 lifting said elongated member and said tie plate;
60 positioning said tie plate over a railroad tie with said pointed, elongated member; and
65 permitting said tie plate to slide from said elongated member.

2. A method according to claim 1 in which:
the step of inserting at least one elongated member includes the step of inserting at least two pointed, elongated members into two apertures in said tie plate and into said ballast beneath the tie plates; and

the step of lifting said tie plate includes the step of pivoting said members about a point to pivot said tie plate about said point.

3. A method according to claim 1 in which the step of inserting at least one pointed, elongated members includes the step of inserting at least two elongated members having a length of at least one-half inch

through said apertures and into said ballast at least one-eighth inch.

4. A method according to claim 3 in which the step of inserting at least two of said pointed members includes the step of inserting at least two pointed mem-

bers having a longest cross-sectional dimension less than 1½ inches through two apertures into said tie plate.
